UNITED STATES PATENT OFFICE.

ARON ELKONIN, OF NEW YORK, N. Y.

DESIGN FOR A FINGER RING.

Application filed May 11, 1925. Serial No. 13,397. Term of patent 7 years.

To all whom it may concern:

Be it known that ARON ELKONIN, a declarant citizen of the United States, subject of the Government of Russia, and resident of the city of New York, in the county of Bronx and State of New York, has invented a new, original, and ornamental Design for Finger Rings, of which the following is a specification, reference being had to the accompanying drawing, forming part thereof, in which—

Fig. 1 is a side view of a finger ring embodying my new design, and

Fig. 2 is a view of the opposite side.

I claim:

The ornamental design for a finger ring as shown.

Dated New York city, May 9th, 1925.

ARON ELKONIN.
